DESIGN FOR A BUS DUCT RUN

William H. Frank, Detroit, Mich., assignor to
Bulldog Electric Products Company, Detroit,
Mich., a corporation of West Virginia

Application April 19, 1934, Serial No. 51,448

Term of patent 14 years

To all whom it may concern:

Be it known that I, William H. Frank, a citizen
of the United States of America, and a resident
of Detroit, county of Wayne, Michigan, have in-
vented new, original, and ornamental Design for
a Bus Duct Run, of which the following is a
specification, reference being had to the accom-
panying drawing.

On the drawing:—

Fig. 1 is a top plan view of fragment of a bus
duct run of my new design;

Fig. 2 is an end view of the same;
Fig. 3 is a sectional view taken on line 3—3
of Fig. 1, and shown to a somewhat enlarged scale.

What I claim is:

The ornamental design for a bus duct run sub-
stantially as shown.

In testimony whereof I affix my signature.

WILLIAM H. FRANK.
